US0D1100287S

(12) **United States Design Patent** (10) Patent No.: **US D1,100,287 S**
(45) Date of Patent: ** Oct. 28, 2025

(54) **SPOTLIGHT**

(71) Applicant: **NINGBO FUTAI ELECTRIC LIMITED**, Zhejiang (CN)

(72) Inventors: **Fujun Qiu**, Zhejiang (CN); **Chaolien Liu**, Zhejiang (CN)

(73) Assignee: **NINGBO FUTAI ELECTRIC LIMITED**, Ningbo (CN)

(**) Term: **15 Years**

(21) Appl. No.: **29/901,065**

(22) Filed: **Aug. 29, 2023**

(30) **Foreign Application Priority Data**

Jun. 7, 2023 (CN) 202330347827.X

(51) LOC (15) Cl. **26-02**

(52) U.S. Cl.

USPC **D26/45**

CLAIM

The ornamental design for a spotlight as shown and described.

DESCRIPTION

FIG. 1 is a perspective view of the spotlight showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a perspective view of the spotlight in a first use state;

FIG. 10 is a perspective view of the spotlight in a second use state;

FIG. 11 is a perspective view of the spotlight in a third use state; and,

FIG. 12 is a side view of the spotlight in a fourth use state. In the drawings, the broken lines depict portions of the spotlight that form no part of the claimed design.

1 Claim, 12 Drawing Sheets
